DOORLOCK

Original Filed April 20, 1929

ELLING ELLINGSON.
By Arthur H. Slee.
ATTY.

UNITED STATES PATENT OFFICE

ELLING ELLINGSON, OF SAN FRANCISCO, CALIFORNIA

DOOR LOCK

Application filed April 20, 1929, Serial No. 356,697. Renewed October 6, 1930.

My invention relates to improvements in locks for doors and the like wherein a latch bolt, movable from a normal door latching position to a door releasing position, is provided with key actuated means operable from the outside and with manually operated means operable from the inside of the door independently of the key actuated means for actuating the latch, and also provided with manually operated means operable from the outside of the door for actuating the latch independently of the key actuated means and the inside operating means, the key actuated means being movable to a locking position preventing the operating of the latch by either manual operating means.

The primary object of my present application is to provide an improved locking mechanism for doors.

Another object is to provide an improved locking device wherein manual operating means are provided for operation from the inside and from the outside of a door independently of a key actuated means operable from the outside of a door for moving a latch to door releasing position or for preventing the operation of said latch.

Another object is to provide an improved device having an actuating member movable in one direction to operate a door latch and in the opposite direction to lock said latch against movement.

A further object is to provide an improved device of the character described which may be locked from the outside against operation from either side by means other than a proper key applied from the outside of the door.

Another object is to provide an improved device of the character described having manually actuated operating means upon both the inside and outside of the door and operating independently of a key actuated means operable from the outside of the door, said key actuated means being operable to prevent opening of the door by either outer or inner manual operating means, and provided also with means operable from the inside of the door to prevent operation of the outside manual operating means.

A further object is to provide an improved

mechanism which is simple and positive in its action and which may be easily assembled and installed.

I accomplish these and other objects by means of the improved device disclosed in the drawings forming a part of the present application wherein like characters of reference are used to designate similar parts throughout the specification and drawings and in which—

Fig. 1 is a broken horizontal section of my improved door lock as installed upon a door;

Fig. 2 is a broken vertical section taken upon the line 2—2 of Fig. 1 in the direction indicated;

Fig. 3 is a broken vertical section taken upon the line 3—3 of Fig. 2 in the direction indicated;

Fig. 4 is a broken detail disclosing the manner in which the key actuated member is moved to locking position;

Fig. 5 is a broken detail disclosing the manner in which the latch bolt is engaged by the knob actuated means; and

Fig. 6 is a broken sectional detail of the plunger and plunger stop.

Referring to the drawings, the numeral 1 is used to designate in general a door having a latch bolt 2 slidably mounted within a casing 3 set within an opening 4 formed in the edge of the door. The bolt 2 is normally held in latching position by a spring 5 and is provided with a U-shape extension 6 extending axially into the opening 4 and guided at its inner end by a reduced portion 7 of the casing 3, said extension being provided with a yoke shaped end 8 having spaced transverse bar portions 8' at the inner end of the extension 6.

An opening 9 is formed transversely through the door to intersect the opening 4, and a recess 11 is formed upon the inner side of the door. A cylinder lock 12 of any suitable construction, such as commonly known, is secured within the opening 9, preferably by means of a plate 13 adapted to seat against the back of the recess 11 and to be secured therein by screws 14. The lock is provided with the usual outer flange 16 seating against a face plate 17 mounted upon the outer face

of the door 1. The lock 12 is provided with the usual rotatable cylinder mounted within a casing and adapted to be operated by a suitable key in the ordinary and well known manner.

5 A post 21 is mounted upon the inner end of the lock 12 in inwardly disposed axial relation to the cylinder of the lock, said post preferably being mounted by means of a 10 mounting plate 22 secured upon the inner end of the lock cylinder by means of screws 23 and having a central opening through which the post 21 extends. A flange 24 formed upon the end of the post 21 is engaged between the 15 plate 22 and the inner end of the lock cylinder.

20 A latch actuating member 26 is rotatably mounted upon the post 21 adjacent the outer face of the plate 22. The member 26 has an 25 arcuate slot 27 formed therein and engaged by a pin 28 carried by the plate 22, the pin 28 preferably being formed as an extension upon the head of one of the screws 23. The member 26 is provided with a latch engaging arm 29 adapted to extend into engagement with the U-shaped extension 6 of the latch bolt 2 and to engage the lower bar portion 8' thereof as best shown in Fig. 2 of the drawings whereby a rotation of the lock cylinder 30 and the plate 22 in a clockwise direction as viewed from the outer side of the door will cause said arm 29 to engage and move the latch bolt to a door releasing position, as indicated in dotted lines.

35 The member 26 is also provided with an actuating arm 31 having a roller 32 mounted thereon, said arm and roller being adapted to be engaged by the upper end of a plunger 33 slidably mounted within the recess 11 and 40 guided by means of a guide plate 34 secured upon the plate 13, preferably by the screws 14 which serve to secure said plate and the lock 12 upon the door. A transverse extension 36 is formed upon the lower end of the 45 plunger 33. A latch lever 37 is pivotally mounted upon the face plate 17 and arranged to extend inwardly through openings 38 and 39 formed in said plate and the door respectively into engagement with the under side of the transverse extension 36 whereby a 50 downward movement of the outer end of the latch lever 37 will cause the plunger 33 to be raised against the pressure of a spring 41 to engage and move the arm 31 and thereby 55 actuate the member 26 to operate the latch as indicated in dotted lines in Fig. 2.

56 The guide 34 is arranged to permit a limited transverse movement of the plunger 33 therein, said plunger normally being held in 60 alignment with the roller 32 by means of a suitable leaf spring 42. The upper end of the plunger is inclined as at 43 whereby a downward pressure of the roller 32 upon the end of the plunger will operate to press the 65 end of the plunger transversely out of alignment with said roller and permit the roller and arm to be moved past the plunger and into an inoperative relation thereto for a purpose hereinafter more fully explained.

66 The member 26 is provided with a stop 44 70 adapted to be moved into the path of the yoke 8 of the latch bolt extension 6, as shown in Fig. 4 of the drawings. The stop 44 is so spaced from the arm 29 that said stop is moved under the upper bar portion 8' and 75 between the side of the yoke 8 when the member 26 is moved to actuate the latch. When the plate 22 is turned in the opposite direction by turning the lock cylinder in a 80 counterclockwise direction by means of its key, the pin 28 is moved through the slot 27 to engage the opposite end of said slot and thereafter to move the member 26 to a locking 85 position as indicated in Fig. 4, thereby causing the arm 29 to be moved between the 90 sides of the yoke 8 and causing the stop 44 to be positioned within the path of the upper bar portion 8'. As the member 26 is thus moved, the actuating arm 31 is moved to displace the plunger 33 laterally and to be moved 95 past said plunger as above explained whereby the plunger is rendered inoperative as a means for actuating the member 26.

100 A second latch actuating member or cam 46 is mounted upon the post 21 adjacent the member 26 and rotatable on said post independently of the member 26. The member 46 is provided with arms 47 extending into the yoke 8 and adapted to engage the bar portions 8' as best shown in Fig. 5 of the 105 drawings, whereby a turning of the member 46 in either direction will cause the latch to be moved to a door releasing position. The member 46 is provided with a socket 48 arranged axially with respect to the post 21 and 110 having its open end disposed toward the inner side of the door. A flange 49 formed upon the end of the post 21 holds the member 46 in operative assembled relation to the post 21.

115 A suitable door knob 51 is mounted upon the inner side of the door 1. The knob 51 is provided with a stem 52, preferably square in cross section, extending into engagement with the open end of the socket 48. A bushing 53 is mounted upon the stem 52 and arranged to be received within a bearing 54 secured upon the inner side of the door. A 120 collar 56 secured upon the stem 52 adjacent the inner edge of the bearing 53 serves to hold the knob and stem in operative position upon the door.

125 A locking member 57 provided with an operating knob 58 is slidably mounted within the door and arranged to engage a notch 59 formed in the side of the plunger 33. The member 57 is arranged to be operated from the inner side of the door and is provided with a notch 61 normally positioned to permit free movement of the plunger to actuate the member 26. By moving the member 57 outwardly 130

through the inner face of the door, the notch 61 is moved out of alignment with the plunger 33, and the member 57 is moved into engagement with the notch 59 as shown in Fig. 5 6 thereby effectually locking said plunger against vertical movement. The member 57 engages the plunger 33 upon the side opposite the spring 42 so as not to interfere with the transverse movement of the plunger. 10 When it is desired to lock the door from the outside, a proper key is inserted into the lock 12 and turned in a counter-clockwise direction. As the cylinder of the lock and the plate 22 are thus turned, the pin 28 first moves 15 along the slot 27 until the opposite end of said slot is engaged and thereafter the member 26 is turned to substantially the position indicated in Fig. 4 of the drawings. At the same time, the arm 31 is pressed against the 20 upper inclined face of the plunger 22, said plunger being displaced against the pressure of the springs 41 and 42 until the roller passes said plunger. To remove the key from the lock it is of course necessary to turn the key 25 back to normal position. As the key is turned back to normal position, the pin 28 moves back along the slot 27 to the position indicated in dotted lines in Fig. 4 and engaging the end of the slot to form a stop operating to prevent 30 rotation of the member 26 in a counter-clockwise direction.

In this position, the stop 44 is disposed immediately in back of the upper bar portion 8' so that any inward movement of the latch bolt 2 will cause said bar portion to strike 35 against the stop 44 and prevent the movement of the latch to its door releasing position. The plunger 33 may be freely operated past the arm 31 and roller 32 without imparting any movement to the member 26, thus preventing the latch from being operated by the 40 lever 37, and the latch is effectually locked against operation by means other than a proper key applied and operated from the 45 outside of the door.

In operation, my improved locking mechanism is constructed and installed substantially as shown and above described. When the member 26 is in normal operative position, the latch bolt 2 may be operated manually from the outside by pressing the latch lever 37 downwardly and thereby lifting the plunger 33 against the arm 31 and roller 32 where by the member 26 is turned and the arm 29 moved to engage and actuate the latch bolt. The latch bolt may also be operated from the outside by inserting a proper key into the cylinder lock 12 and turning said key and the lock cylinder in a clockwise direction, 50 thereby causing the pin 28 to be moved to the end of the slot 27 and then to operate the member 26 which in turn actuates the latch. The latch is operated from the inside of the door by turning the knob 51 in either direction. The slot 27 normally permits the mem-

ber 26 to be moved past the pin 28, thereby permitting said member to be actuated by the plunger independently of the pin 28 and the lock 12.

If it is desired to lock the door from the inside so that it cannot be opened manually by means of the latch lever 37, the lock member 57 is moved outwardly to cause said member to engage the notch 59 and thereby prevent movement of the plunger 33 to actuate the member 26. The blocking of the plunger 33 however does not interfere with the movement of the member 26 independently of said plunger and the latch may be operated by a proper key as above described. 70

To move the member 26 from its locking to its normal position, the lock cylinder is turned by its key in a clockwise direction. The member 26 is turned by the pin 28 and the arm 31 and roller 32 forced against the side of the plunger 33 until said plunger is pressed laterally against the pressure of the spring 42 sufficiently to permit said roller to pass the plunger and move into alignment with the end of said plunger. At the same 80 time the stop 44 is moved out of the path of the yoke portion 8' and the arm 29 is moved to operative position adjacent the lower bar portion 8' whereby a further turning of the key will cause the latch to be actuated as 85 above described.

The specific details of construction of my improved door lock as illustrated and described may of course be modified in a number of ways without departing from the spirit 90 of my invention. I therefore desire to avail myself of all such modifications as may fall within the scope of the appended claims.

Having thus described my invention what I claim as new and desire to secure by Letters Patent is—

1. A door lock comprising a latch bolt slidably mounted within the edge of a door and movable from a normal door securing position to a door releasing position; an actuating member rotatably mounted within the door and provided with a latch actuating arm adapted to engage and move the latch when the member is turned in one direction; a stop carried by said member and adapted to be moved into the path of the latch bolt to prevent movement thereof when said member is turned in the opposite direction to a locking position; key actuated means mounted upon the door and operable from the outer side of the door for turning the actuating member; a second actuating member mounted adjacent the first mentioned actuating member and provided with actuating arms adapted to engage and move the latch bolt to door releasing position when turned in either direction; knob actuated means for turning said second actuating member independently of the first member and the key actuating means; and lever 100

actuated means operable from the outer side of the door for turning the first actuating member in a latch releasing direction independently of the key actuated means and of the knob actuated means.

2. A door lock comprising a latch bolt slidably mounted within the edge of a door and movable from a normal door securing position to a door releasing position; an actuating member rotatably mounted within the door and provided with a latch actuating arm adapted to engage and move the latch when the member is turned in one direction; a stop carried by said member and adapted to be moved into the path of the latch bolt to prevent movement thereof when said member is turned in the opposite direction to a locking position; key actuated means mounted upon the door and operable from the outer side of the door for turning the actuating member; a second actuating member mounted adjacent the first mentioned actuating member and provided with actuating arms adapted to engage and move the latch bolt to a door releasing position when turned in either direction; knob actuated means for turning said second actuating member independently of the first member and the key actuating means; a plunger mounted within the door; a lever operable from the outer side of the door for actuating the plunger; and an arm carried by the first mentioned actuating member and adapted to be engaged by the plunger whereby the latch bolt may be actuated independently of the key actuated means and of the knob actuated means.
3. A door lock comprising a latch bolt slidably mounted within the edge of a door and movable from a normal door securing position to a door releasing position; an actuating member rotatably mounted within the door and provided with a latch actuating arm adapted to engage and move the latch when the member is turned in one direction; a stop carried by said member and adapted to be moved into the path of the latch bolt to prevent movement thereof when said member is turned in the opposite direction to a locking position; key actuated means mounted upon the door and operable from the outer side of the door for turning the actuating member; a second actuating member mounted adjacent the first mentioned actuating member and provided with actuating arms adapted to engage and move the latch bolt to a door releasing position when turned in either direction; knob actuated means for turning said second actuating member independently of the first member and the key actuated means; a plunger mounted within the door; a lever operable from the outer side of the door for actuating the plunger;

an arm carried by the first mentioned actuating member and adapted to be engaged by the plunger whereby the latch bolt may be actuated independently of the key actuated means and of the knob actuated means, said arm being moved out of the path of the plunger when the actuating member is turned to its locking position; and means operable from the inner side of the door for securing the plunger against movement.

4. A door lock comprising a latch bolt slidably mounted within the edge of a door and movable from a normal door securing position to a door releasing position; a key actuated cylinder lock mounted within the outer face of the door and provided with an inwardly disposed extension; a latch actuating member rotatably mounted upon the extension; a pin secured to the lock cylinder and engaging an arcuate slot formed in the actuating member; a latch actuating arm formed upon said member and adapted to engage and move the latch bolt when the cylinder lock and actuating member are turned in one direction; a stop formed upon the actuating member and adapted to be moved into the path of the latch bolt to prevent movement thereof when the lock cylinder and the actuating member is turned in the opposite direction to a locking position; a lever actuated plunger operable from the outer side of the door for operating the actuating member independently of the key actuated means, the slot in said actuating member being adapted to permit movement of said member past the pin; and knob actuated means operable from the inside of the door for actuating the bolt independently of the key actuated member when said member is in a normal position.

5. A door lock comprising a latch bolt slidably mounted within the edge of a door; a key actuated cylinder lock mounted within the outer face of the door and provided with an inwardly disposed extension; a latch actuating member rotatably mounted upon the extension; a pin secured to the lock cylinder and engaging an arcuate slot in the actuating member; a latch actuating arm formed upon said member and adapted to engage and move the latch bolt when the cylinder of the lock and the actuating member are turned in one direction; a stop formed upon the actuating member and adapted to be moved into the path of the latch bolt to prevent movement thereof when the lock cylinder and the actuating member are turned in the opposite direction to a locking position; a second actuating member rotatably mounted upon the extension adjacent the lock actuated member, said second actuating member being provided with arms adapted to engage and move the latch to a door releasing position when said member is turned in either direction; said member also being provided with an

axially disposed socket opening toward the inner side of the door; and a knob mounted upon the inner side of the door and provided with a stem engaging the socket for turning said second actuating member independently of the lock actuated member when said lock actuated member is in normal position.

6. A door lock comprising a latch bolt slidably mounted within the edge of a door; a key actuated cylinder lock mounted within the outer face of the door and provided with an inwardly disposed extension; a latch actuating member rotatably mounted upon the extension; a pin secured to the lock cylinder and engaging an arcuate slot in the actuating member; a latch actuating arm formed upon said member and adapted to engage and move the latch bolt when the cylinder of the lock and the actuating member are turned in one direction; a stop formed upon the actuating member and adapted to be moved into the path of the latch bolt to prevent movement thereof when the lock cylinder and the actuating member are turned in the opposite direction to a locking position; a second actuating member rotatably mounted upon the extension adjacent the lock actuated member, said second actuating member being provided with arms adapted to engage and move the latch to a door releasing position when said member is turned in either direction, said member also being provided with an axially disposed socket opening toward the inner side of the door; a knob mounted upon the inner side of the door and provided with a stem engaging the socket for turning said second actuating member independently of the lock actuated member when said lock actuated member is in normal position; a plunger slidably mounted within the door; an arm carried by the lock actuated member and adapted to be engaged by the plunger, said plunger being adapted to be displaced laterally by said arm and out of engagement with the plunger when said actuating member is turned to locking position; and a pivoted lever operable from the outer side of the door and engaging the plunger for moving the same to operate the actuating member and latch bolt independently of the cylinder lock.

7. In a door lock, the combination with a door latch slidably mounted within the edge of a door and movable from normal latching position to door releasing position, of an actuating member rotatably mounted within the door and movable in one direction to move the latch to door releasing position and in the opposite direction to a locking position providing a stop preventing the operation of the latch; key actuated means operable from the outer side of the door for moving the actuating member and adapted to permit a limited independent movement of said member; an arm carried by the actuating

ing member; a plunger slidably mounted within the door and movable longitudinally into engagement with the arm to move the actuating member in a latch releasing direction, said plunger being laterally movable to permit the arm to be moved therewith when the actuating member is turned to its locking position; and a lever operable from the outer side of the door and engaging the plunger whereby the plunger and the actuating member may be operated to actuate the latch independently of the key actuating means.

8. In a door lock, the combination with a door latch slidably mounted within the edge of a door and movable from normal latching position to door releasing position, of an actuating member rotatably mounted within the door and movable in one direction to move the latch to door releasing position and in the opposite direction to a locking position providing a stop preventing the operation of the latch; key actuated means operable from the outer side of the door for moving the actuating member and adapted to permit a limited independent movement of said member; an arm carried by the actuating member; a plunger slidably mounted within the door and movable longitudinally into engagement with the arm to move the actuating member in a latch releasing direction, said plunger being laterally movable to permit the arm to be moved therewith when the actuating member is turned to its locking position; a lever operable from the outer side of the door and engaging the plunger whereby the plunger and the actuating member may be operated to actuate the latch independently of the key actuating means; and knob actuated means operable from the inside of the door to actuate the latch independently of the actuating member.

9. In a door lock, the combination with a door latch slidably mounted within the edge of a door and movable from normal latching position to door releasing position, of an actuating member rotatably mounted within the door and movable in one direction to move the latch to door releasing position and in the opposite direction to a locking position providing a stop preventing the operation of the latch; key actuated means operable from the outer side of the door for moving the actuating member and adapted to permit a limited independent movement of said member; an arm carried by the actuating member; a plunger slidably mounted within the door and movable longitudinally into engagement with the arm to move the actuating member in a latch releasing direction, said plunger being laterally movable to permit the arm to be moved therewith when the actuating member is turned to its locking position; a lever operable from the outer side of the door and engaging the plunger whereby the plunger and the actuating member may be operated

to actuate the latch independently of the key actuating means; knob actuated means operable from the inside of the door to actuate the latch independently of the actuating member; and means operable from the inside of the door for preventing the operation of the lever and plunger.

In witness whereof, I hereunto set my signature.
